Primary Examiner — Marianne Pandozzi(74) *Attorney, Agent, or Firm* — Law Office of Karen Dana Oster, LLC(57) **CLAIM**

The ornamental design for a cold brew coffee system, as shown and described.

DESCRIPTION

FIG. 1 is a perspective view of the cold brew coffee system of my new design;

FIG. 2 is a bottom perspective view thereof;

FIG. 3 is an exploded top perspective view thereof;

FIG. 4 is an exploded bottom perspective view thereof;

FIG. 5 is a front view thereof;

FIG. 6 is a rear view thereof;

FIG. 7 is a side view thereof, the opposite view being a mirror image thereof.

FIG. 8 is a top view thereof; and,

FIG. 9 is a bottom view thereof.

The broken lines depict portions of the cold brew coffee system that form no part of the claimed design.
